UNITED STATES PATENT OFFICE.

JAKOB HÄUSERMANN, OF STETTEN, NEAR LÖRRACH, GERMANY, ASSIGNOR TO THE FIRM OF GEBR. STÄUBLE, OF HORGAN, CANTON OF ZURICH, SWITZERLAND.

RIBBON-LOOM.

1,072,944.

Specification of Letters Patent.

Patented Sept. 9, 1913.

Application filed February 20, 1912. Serial No. 678,962.

To all whom it may concern:

Be it known that I, JAKOB HÄUSERMANN, a citizen of the Swiss Republic, and resident of Stetten, near Lörrach, in the Grand 5 Duchy of Baden, Germany, have invented new and useful Improvements in Ribbon-Looms, of which the following is a full, clear, and exact specification.

In ribbon looms it frequently happens 10 that for certain ribbon types it is required to operate the heddles without the dobby apparatus according to a fundamental shedding motion by means of the ordinary cross-wise arranged shedding cams, this cam gear being hitherto placed in the lower part of 15 the loom frame-work and being set into operation when the mode of operating the heddles is to be changed from the dobby controlled shedding to the said cam controlled shedding. In shedding cam gears 20 of this kind, there are, however, several disadvantages. Firstly these gears are, from a constructional point of view, extremely complicated; then again when the shed is 25 to remain open during two, three, or more successive picks, it is necessary to correspondingly alter the driving connection between the shedding cam gear and the loom 30 shaft as well as the arrangement of the eccentric disks or cams, which requires the expenditure of considerable time, labor and material.

Now the present invention relates to a 35 cam shedding apparatus for ribbon looms, which as usual allows of the ordinary fundamental shedding motion (instead of the dobby controlled shedding motion), but this is distinguished from the ordinary cam gears of this kind in that its operation is 40 automatically controlled by a pattern card having perforations according to the fundamental shedding so that it may be automatically brought into and out of gear according to the pattern of said card. The 45 whole construction of such an arrangement is extremely simple. Owing to the control of the cam shedding apparatus by means of a pattern card a simple means is at hand whereby according to the pattern of the 50 card, when the cam shedding apparatus is in gear, this latter may at any time be temporarily put out of gear to allow the shed to remain open for any desired number of picks.

55 The accompanying drawings illustrate

one constructional example of the subject of the present invention, which is here combined with a ribbon loom dobby apparatus and this combination allows of an especial simplicity of construction in that it allows 60 of the use of the dobby treadles for the cam shedding operation and in that the card of the dobby may at the same time constitute the pattern card for the control of the cam shedding apparatus; however, the cam shedding apparatus could also be arranged independently of the dobby.

Figure 1 is a side view of the said dobby with its members in a first position. Fig. 2 is a longitudinal section through the 70 dobby in the position of the members shown in Fig. 1. Fig. 3 is a second longitudinal section showing a different positioning of the parts. Fig. 4 is a side view of the dobby similar to that shown in Fig. 1, but 75 showing a different position of the parts. Fig. 5 shows a detail view of a ratchet and pawl mechanism.

1 is the frame of the dobby in which an oscillating shaft 3 provided with a driving 80 arm 2 (Fig. 1) is mounted. The oscillating shaft 3 carries further two beam-levers 4 which are connected by links 5 with the two lifting blades 6 and 7. Connecting rods 8 are pivoted to the beam-levers 4 and impart the to and fro movement of the beam-levers to pendulum levers 10 pivoted at 9. These levers 10 carry pins 11 which engage in cam slots 12 of two levers 14 pivoted at 13. The free ends of the levers 14 are connected with the carrying rods 17 of the pattern card cylinder 15 moving up and down in eyelet lugs 16 on the frame 1. The card cylinder 15, together with the card passing over it, acts in its upward movement on 95 the pins or needles 18 and causes, according to the particular selection due to the perforation of the card, a greater or less number of locking levers 100 (Fig. 2) arranged beneath and corresponding in number to the 100 lifting hooks 19 to swing out and thus bring them out of the range of a locking nose 99 of the corresponding hooks 19 advanced through the lower blade 6 and to allow these hooks 19 which have just been reached by the upper blade 7, to follow the then retreating upper blade 7 to which they have attached themselves, while all the other hooks 19 drawn forward by the knife 6 are 105 locked by the corresponding levers 100 110

which have not been disengaged. The hooks 19 are connected to the usual treadles 21. All but one of these treadles have the heddles hung upon them, their return movement, owing to the pull of the heddles being limited by means of a stopping bar 44.

Above the lifting hooks 19 the particular cam shedding device is mounted in the frame 1 of the dobby (Fig. 2). This consists of a plurality of crosswise arranged cams 34 mounted by pairs on a shaft 31, which are slightly displaced relatively one to another and united in a solid whole by means of bolts. The cams 34 are designed to coöperate with roller carrying arms 38 which are connected to the treadles 21 necessary for the fundamental shedding motion. The shaft 31 is hollow and slides upon a revoluble shaft 42 by means of a groove and key. The shaft 42 carries a ratchet wheel 30 by which means at each stroke it is turned a quarter of a revolution, for which purpose a pawl 28 pivoted to a bell crank lever 32 coöperates with the ratchet wheel 30 in such a manner that at each to and fro movement it moves the ratchet wheel one step forward. The bell crank lever 32 is driven by a rod 33 actuated by an eccentric (not shown) on the main shaft 30 of the loom.

The free treadle 21, that is to say, that one on which no heddle is hooked, but which however is suitably weighted, has a pushing pawl 22 pivoted to it which normally operates upon a ratchet wheel 23 revolubly mounted within the frame 1. An unforeseen turning of the ratchet wheel 23 is prevented by means of a spring controlled locking pawl 24. The ratchet wheel 23 is mounted upon a revoluble shaft 25 mounted in the frame-work 1, which shaft passes outside the framework and carries there a lifting cam 26 which supports a vertically guided controlling rod 27. The upper end of this controlling rod 27 is so arranged relatively to the ratchet wheel 30 that it acts as a guide for the pawl 28 when the control rod 27 is lifted, in such a manner that the pawl 28 at the next following return stroke cannot engage with the ratchet wheel 30 to move it forward, whereby the shedding cams 34 will remain fixed in the position they have taken up. If, on the other hand, the controlling rod 27 falls, then it releases the pawl 28 and this can then move the wheel 30 and the shedding cams 34.

The operation of the controlling rod 27 depends on the position of the lifting cam 26 and the position of this latter depends upon the movement of the corresponding treadle 21 imparted to it by means of the pawl and ratchet mechanism 22, 23. The position of the treadle 21 is controlled from the pattern card by means of the corresponding lifting hook 19, the correspond-

ing locking lever 100 and the corresponding needle 18. The pattern card has along one edge a particular perforation pattern in such a manner that it has perforations so long as the cam shedding gear shall not be set in operation. 70

Normally the cam shedding gear is put out of operation as the cams 34 are displaced sufficiently to one side owing to the shaft 31 sliding along the shaft 42 so that they are withdrawn from the range of the treadle arms 38. The card controls by means of the needles 18, the levers 100 and the lifting hooks 19, the movement of the heddles under the control of the lifting blades 6 and 7. As the operation of these hooks and blades does not affect the present invention it is not necessary to describe these in further detail. Should now, for a particular work, the shedding be operated by means of the cams 34 (instead of the dobby), then the cams 34 are pushed into their operative position relative to the treadle arms 38, while the card is replaced by another so perforated that those hooks whose treadles 21 are now made dependent upon the cam shedding gear, no longer work as regards the treadle movement, but on the other hand that hook 19 which controls the engaging and disengaging of the cam shedding gear and which is connected to the above mentioned heddleless counter-weighted treadle 21, is operated by the card according to the wished for fundamental shedding operation. This latter hook will 106 be called cam shedding hook in the following to differentiate it from the others. 95

Consider that the machine lies ready for operation by means of the cam shedding gear (Fig. 1). The lever 32 moving to and fro moves each time the shedding cams 34 forward 90° by means of the pawl 28 and the wheel 30 so that the change of shed takes place according to the well known cam shedding operation. If, now, during this mode of operation the card disengages the lever 100 corresponding to the cam shedding hook from this latter, then this cam shedding hook (in a similar manner to the remaining hooks in the case of dobby control) which as above has been reached by the upper blade 7, goes back with this latter and then the treadle 21 connected to it moves the pushing pawl 22 backward in order to bring it into operative position relatively to the wheel 23. 110 During the next following forward movement of the blade 6, the cam shedding hook is again brought forward which causes the pawl 22 to be engaged with the wheel 23 in the manner shown in Fig. 3 and thereby the lifting cam 26 will be turned 90° from the position shown in Fig. 1 to that shown in Fig. 4. By this means the controlling rod 27 is lifted to such an extent that it forms a guide for the continuously recipro- 130

cating pawl 28 in such a manner that this can no longer come into engagement with the ratchet wheel 30. Directly this takes place the cam shedding gear is no longer actuated as its drive mechanism is disengaged; the shed remains therefore open in the position into which it had last been brought so that one, two, or more picks could take place, and this condition of affairs remains unaltered until the card causes a new disengagement of the cam shedding hook, which hook has meanwhile hooked itself upon the corresponding locking lever 100, whereby in a similar manner as above stated a fresh movement of the wheel 23 takes place which causes the lifting cam 26 to again be turned into the position shown in Fig. 1 in order to allow the controlling rod 27 to be lowered and to allow the pawl 28 to again come into engagement with the ratchet wheel 30 and operate the step by step forward movement of the shedding cams 34. It may be seen from the above that the bringing into and out of operation of the shedding cam gear is controlled automatically from the card by means of the above mentioned free hook or cam shedding hook.

The different positions of the shedding cams 34, when being in operation, are secured by a locking spring 37 engaging with a locking wheel 36 on the shaft 42.

What I claim is:

1. In dobby apparatus for ribbon looms, the combination with heddle operating members of a normally inoperative shedding cam gear capable of being brought into an operative condition with regard to said heddle operating members for the operation thereof, a driving mechanism for said shedding cam gear and an automatic, card controlled engaging and disengaging device for said driving mechanism, substantially as described.
2. In dobby apparatus for ribbon looms, the combination with heddle operating members of a normally inoperative shedding cam gear capable of being brought into an operative condition with regard to said heddle operating members for the operation thereof, a pawl and ratchet mechanism for driving said shedding cam gear and an automatic, card controlled engaging and disengaging device for said driving mechanism, substantially as described.
3. In dobby apparatus for ribbon looms,

the combination with heddle operating members of a normally inoperative shedding cam gear capable of being brought into an operative condition with regard to said heddle operating members for the operation thereof, a pawl and ratchet mechanism for driving said shedding cam gear, a controlling member for the pawl of said mechanism to disengage it when being lifted and to allow of its engagement with the ratchet when being lowered, a rotary cam for lifting and lowering said controlling member, and card controlled means for causing intermittent rotation of said rotary cam under the control of said card, substantially as described.

4. In dobby apparatus for ribbon looms, the combination with heddle operating treadles of hooks connected thereto, reciprocating blades for operating said hooks, card controlled selecting means for selecting the hooks to be operated, a shedding cam gear normally in inoperative condition, but capable of being brought into an operative condition with regard to said treadles when they are to be operated without hook control, a pawl and ratchet mechanism for driving said shedding cam gear, a controlling member for the pawl of said mechanism to disengage it when being lifted and to allow of its engagement with the ratchet when being lowered, a rotary cam for lifting and lowering said controlling member, and card controlled means for causing intermittent rotation of said rotary cam under the control of said card, substantially as described.

5. In ribbon looms, a dobby having heddle operating levers, an auxiliary rotary shaft mounted in the frame of said dobby, a shedding cam gear slidably mounted on said shaft, being normally in inoperative position, but capable of being shifted into operative position with regard to said heddle operating levers, a drive mechanism for driving said shedding cam gear shaft independently of the dobby control, and an automatic card controlled device for temporarily engaging and disengaging said drive mechanism, substantially as described.

In witness whereof I have hereunto signed my name this 2d day of February 1912, in the presence of two subscribing witnesses.

JAKOB HÄUSERMANN.
